[57] ABSTRACT

An electrical switch including a base having a rotor mounted for angular movement thereon. A first set of electrical contacts is operable by angular movement of the rotor relative to the base, and an operating lever is pivotally mounted on the rotor for movement relative to the rotor about an axis at right angles to the axis of movement of the rotor. The lever is coupled to a slider capable of sliding movement relative to the base, and further electrical contacts are operable by the slider in response to sliding movement thereof. The operating lever is coupled to the slider in such a manner that movement of the lever in a direction parallel to its pivot axis takes place relative to the slider, and so moves the rotor relative to the base to operate the first set of contacts.

**VEHICLE DIRECTION SWITCH WITH
AUTOMATIC RETURN AND HEADLIGHT
DIMMER CONTROL**

This invention relates to electrical switches for road vehicles.

A switch according to the invention includes a base, a rotor mounted for angular movement on the base, a first set of electrical contacts operable by movement of the rotor relative to the base, an operating lever pivotally mounted on the rotor for movement relative to the rotor about an axis generally at right angles to the axis of movement of the rotor relative to the base, a slider mounted on the base for sliding movement relative thereto in a direction generally parallel with the axis about which the rotor can move, and a second set of contacts operable by movement of the slider relative to the base, the operating lever being coupled to said slider in such a manner that pivotal movement of the lever relative to the rotor moves said slider while movement of the lever in plane parallel to the pivotal axis of the lever takes place relative to the slider and moves the rotor relative to the base.

One example of the invention is illustrated in the accompanying drawings wherein,

FIG. 1 is a plan view of a direction indicator switch,
FIG. 2 is a sectional view on the line 2-2 in FIG. 1,

FIG. 3 is an enlarged diagrammatic plan view of part of the switch shown in FIG. 1,

FIG. 3A is a fragmentary view illustrating an alternative arrangement to that shown in FIG. 3.

FIG. 4 is a diagrammatic side elevational view of the switch shown in FIG. 1,

FIG. 5 is a plan view of a part of the switch shown in FIG. 1, and

FIG. 6 is a partly diagrammatic view in the direction of arrow A in FIG. 5.

Referring to the drawings, the switch includes a moulded synthetic resin body 11 which is adapted at 12 to be secured to the stationary outer part of the steering column of a road vehicle. The body 11 defines a collar which encircles the stationary outer part of the steering column of the road vehicle, and rotatably mounted on the body 11 is a moulded synthetic resin striker sleeve 13, the striker sleeve 13 being keyed to the rotatable part of the steering column, so as to rotate therewith. Mounted for rotation on the body 11 at about an axis parallel to the axis of the sleeve 13 is a moulded synthetic resin rotor 14 to which is pivotally connected an operating lever 15. The operating lever 15 extends outwardly from the switch, and is pivotally connected to the rotor 14 for movement about an axis at right angles to the pivotal axis of the rotor 14, the innermost end of the lever 15 being received in a pivot piece 16 coupled to the rotor 14 for said pivotal movement.

Engaged as a snap fit with the rotor 14, and extending generally towards the sleeve 13 are a pair of moulded synthetic resin, resilient cancelling legs 17 each of which terminates adjacent the sleeve 13. First and second sets of contacts 18, 19 are operable in response to movement of the rotor, relative to the body 11, the contacts 18, 19 being independent of one another and serving different functions in use. The contacts 18 control the direction indicator function of the vehicle utilizing the switch and the contacts 19 control parking light function of the vehicle. The rotor has

three stable positions relative to the body 11, a first, central position wherein neither the contacts 18 nor the contacts 19 are operated, a second, operative position achieved by moving the rotor 14 relative to the body 11 in one angular direction, to complete, in use, the circuits to the direction indicator lamps on one side of the vehicle through the contacts 18, and a third, operative position achieved by moving the rotor in the opposite angular direction from its central position and wherein the contacts 18 are operated to complete the circuits to the direction indicator lamps on the opposite side of vehicle. The rotor 14 is formed with a first radially extending bore 21 which houses a compression spring 22 urging a ball 23 into engagement with a cam track 24 formed on a wall of the body 11. The cam track 24 includes three angularly spaced depressions, the ball 23 and the cam track 24 constituting detent means defining the first, second and third stable positions of the rotor 14 relative to the body 11. When the vehicle is parked with its side lamp switch closed, then movement of the rotor to its second position causes the side lights on one side of the vehicle only to be energized through the contacts 19, while with the rotor in its third position only the side lamps on the opposite side are energized. In the first central position of the rotor all of the side lamps are energized.

Movement of the rotor 14 relative to the body 11 to either of its second and third positions causes the ball 23 to ride from the central depression of the cam track 24 into one or other of the outermost depressions of the cam track 24, and moves one or other of the legs 17 into the path of movement of a striker (not shown) on the outer surface of the sleeve 13. As stated above the contacts 18 are used to control the direction indicator lamps on opposite sides respectively of the vehicle, and during rotation of the steering wheel of the vehicle in a direction to negotiate the turn indicated when the rotor is in its second or third position, then the striker on the sleeve 13 engages the leg 17 which is in its path of movement, and flexes the leg outwardly to permit the striker to pass. However, when the turn has been negotiated and the steering wheel is being returned to its straight ahead position, the striker engages the outer surface of the respective leg 17, and flexes the leg 17 against a stop on the rotor 14, whereafter further flexure of the leg 17 is resisted. The force exerted on the end of the leg 17 by the striker, in returning the steering wheel to its straight ahead position, creates a turning moment about the pivotal axis of the rotor 14, and returns the rotor 14 to its central position wherein the contacts 18 are inoperative, and the leg 17 is out of the path of movement of the striker.

The contacts 18 are arranged to be operated during the movement of the rotor 14 from its central position to either of its second or third operative positions, and before the rotor 14 reaches said operative positions. The rotor 14 is formed with a second radially extending bore 25 which houses a compression spring 26 urging a further ball 27 into a channel 28 in the wall of the body 11. When the rotor is in its central position, the ball 27 is adjacent the mid-point of the channel 28, and the length of the channel 28 is shorter than the distance between the outermost depressions of the cam track 24. Thus, during movement of the rotor 14 to either of its second or third positions before the ball 23 engages

either of the outermost depressions in the cam track 24, the ball 27 will engage one or other of the ends of the channel 28 and the switch operator will feel a resistance to movement of the rotor 14 as the ball 27 is forced back into the bore 25 against the action of the spring 26, as the ball 27 engages one or other of the ends of the channel 28. The contacts 18, are operated in the amount of movement necessary to engage the ball 27 with the ends of the channel 28, and so at the point in the movement of the rotor 14 at which the operator feels resistance to movement, the contacts 18 will have been operated. However, if at the point at which the operator feels resistance to movement of the rotor 14, the operator releases the lever 15 then the rotor 14 will be returned to its central position, wherein the contacts 18 inoperative, by the action of the ball 23 in the central depression of the cam track 24. Thus the switch operator can maintain the rotor 14 in a position wherein the desired indicator lamps of the vehicle are operative, but wherein the rotor 14 will be returned to its central position upon release of the lever 15, without the necessity of cancellation of the switch by the striker on the sleeve 13. This feature is particularly useful where the vehicle is to make a small directional change involving little movement of the steering wheel of the vehicle, for example, changing lanes on a motorway. Coacting stops are provided on the rotor and the body for preventing movement of the rotor relative to the body beyond its second and third positions. Ball 27 can be replaced by a plunger as shown in FIG. 3A.

The flasher unit which causes flashing of the direction indicator lamps of the vehicle is carried by the body 11 and is plugged into a printed circuit board on the body 11, the printed circuit board completing the circuit between the unit and the contacts 18.

The switch is provided with a metal cover plate 29 which extends parallel with the body 11, and which constitutes a second journal for the sleeve 13 and the pivot piece 14. Slidably mounted in the plate 29 and the body 11, and extending generally at right angles to the body 11 is a slider 31 (FIGS. 5 and 6) which is of arcuate cross-section. Intermediate its ends the slider 31 is formed with a transversely extending elongated slot 32 through which the lever 15 extends, and at its end remote from the plate 29 the slider 31 is formed with three parallel, integral fingers 33,34,35 respectively. The fingers 33,35 extend through respective passages in the body 11, and serve to locate the lower end of the slider 31 for sliding movement in the body 11, the upper end of the slider 31 being received in a slot in the plate 29, the body 11 and the plate 29 supporting the slider 31 against movement other than in a direction generally parallel with the pivotal axis of the rotor 14. The finger 34 of the slider 31 is resilient, and extends through an aperture in the body 11 with clearance. The face of the finger 34 presented towards the rotor 14 is formed with a pair of transversely extending grooves 36,37 which are spaced apart by a conical, transversely extending rib 38, and the surface of the slider 31 containing the grooves 36,37 is engaged by a relatively rigid projection 39 integral with the body 11. The arrangement is such that the finger 34 is stressed into engagement with the projection 39 upon assembly of the switch, with the projection 39 engaged in one or other of the grooves 36,37 of the finger 34.

The opposite longer walls of the slots 32 in the slider 31 grip the lever 15, so that the slider 31 is moved in a direction parallel with the pivotal axis of the rotor 14 by movement of the lever 15 about its pivotal axis relative to the rotor 14. The longer walls of the slots 32 are relieved, so that they make substantially only line contact with the lever 15.

The fingers 33,35 of the slider 31 project from the lower surface of the body 11, and are engageable with respective leaf spring contacts 41,42. The leaf spring contacts 41,42 are secured at one end to the body 11, and are engageable at their other ends with respective fixed contacts (not shown) also supported by the body 11. In use, the contacts 41,42 together with their respective fixed contacts are connected in the headlamps circuit of the road vehicle, and control the main beam, dipped beam, and main beam flash facilities of the vehicle, under the action of the fingers 33,35 of the slider 31. When the main lighting control switch of the vehicle is in its on position, and the slider 31 is in a position wherein the projection 39 is engaged in the groove 37, then the main beam filaments of the headlamps will be energized. In order to switch off the main beams, and energize the dipped beam filaments of the headlamps the lever 15 is moved relative to the rotor 14 to move the slider 31 upwardly, and during the upward movement of the slider 31 the projection 39 rides over the rib 38 and into the groove 36, the finger 34 being flexed to permit the rib 38 to pass the projection 39. With the projection 39 engaged in the groove 36, the fingers 33,35 are in such a position that the dipped beam filaments of the headlamps of the vehicle are energized. The grooves 36,37 together with the projection 39 constitute detent means defining the two stable positions of the slider 31 relative to the body 11. Further movement of the slider 31 in an upward direction, under the action of the lever 15, causes the finger 34 to be flexed as the projection 39 rides up the wall of the groove 36 remote from the groove 37. This movement of the slider 31 causes engagement of the leaf spring contact 41 with a feed contact carried by the body 11. The feed contact is not controlled by the main lighting switch, and so when it is engaged by the leaf spring contact 41 the main beam circuit of the headlamps of the vehicle is completed regardless of the position of the main lighting switch. Since the projection 39 is engaged with the wall of the groove 36, and the finger 34 is flexed, then this position of the slider 31 is unstable, and upon release of the lever 15 the slider 31 will be returned to the position wherein the projection 39 engages in the groove 36. Thus, the main beams of the headlamps of the vehicle can be flashed by moving the lever 15 to move the slider 31 momentarily beyond its second position.

The slider 31 is provided with outwardly directed shoulders 43,44 which are engageable with the cover 29 and the body 11 respectively. During movement of the slider 31 relative to the body 11, the shoulder 43 engages the cover 29 to prevent movement of the slider 31 beyond the main beam flash position, and the shoulder 44 engages the body 11 during movement of the slider 31 in the opposite direction to prevent movement of the slider beyond the position wherein the projection 39 engages in the groove 37.

The operating lever 15 is hollow, and is formed from conductive material, the outer surface of the lever 15 being coated with insulating material. At its end remote from the body 11 the operating lever carries a pair of contacts, one of which is electrically connected to the lever 15, and the other one of which is insulated from the lever 15 and connected to an insulating lead which extends within the lever 15. The two contacts at the free end of the lever 15 can be bridged by an operating member which is slidably mounted on the lever 15, and which is urged to a position clear of the contacts by a spring. The two contacts can, in use, be electrically connected in the horn circuit the windscreen washer circuit or a smaller circuit of the vehicle, so that the circuit can be operated by moving the operating member relative to the lever 15 against the action of the spring. In a modification, the lever 15 is mounted for axial movement relative to the rotor 14 and adjacent the inner end of the lever 15 are a pair of contacts which are operable by the inner end of the lever 15. Thus, in the modification, in order to operate said circuit the lever 15 is moved bodily inwardly relative to the body 11, so that the inner end of the lever 15 operates the contacts. In the modification the pivot piece 16 is replaced by a pivot pin extending through a slot in the lever.

The body 11 and the plate 29 include provision for mounting thereon further switches for example, for controlling the windscreen wipers the lights and hazard warning facility of the road vehicle. The further switches would be mounted on the body 11 and/or the plate 29 on the opposite side of the steering column of the vehicle from the rotor 14, with the operating member of, for example, the windscreen wiper switch extending outwardly from the steering column generally diametrically opposite the operating lever 15. Where the switch has a hazard warning switch associated therewith, the flasher unit of the hazard warning system is carried by the body 11 and is plugged into a printed circuit through which connections are made to the unit.

In a further modification the cam track 24 and the channel 28 are formed in the upper surface of the body 11 and the balls 23,27 are spring urged in a vertical direction into engagement with the cam track 24 and the channel 28 respectively.

In a still further modification the ball 27 is replaced by a synthetic resin plunger which is resiliently urged into a mating channel formed in the body 11, and the plunger can be positioned so as to extend either vertically or radially with respect to the rotor 14.

Having thus described my invention what I claim as new and desire to secure by Letters Patent is:

1. An electrical switch including a base, a rotor, means mounting the rotor for angular movement on the base, a first set of electrical contacts supported by the base, angular movement of the rotor relative to the base operating said first set of contacts, an operating lever, means pivotally mounting the operating lever on the rotor for movement relative to the rotor about an axis generally at right angles to the axis of movement of the rotor relative to the base, a slider, means mounting the slider on the base for sliding movement relative thereto in a direction generally parallel with the axis about which the rotor can move angularly relative to

the base, a second set of electrical contacts supported by the base, movement of the slider relative to the base operating said second set of contacts, a fixed detent component carried by the base, a movable detent component carried by said slider and co-operating with the fixed detent component to define operative positions of the slider relative to the base, and, means coupling the operating lever to said slider in such a manner that pivotal movement of the lever relative to the rotor moves the slider relative to the base to operate said second set of contacts, whereas movement of the operating lever in a plane parallel to the pivotal axis of the lever takes place relative to the slider, and moves the rotor angularly relative to the base to operate the first set of electrical contacts.

2. A switch as claimed in claim 1 wherein said fixed detent component comprises a fixed projection on the base and said movable detent component comprises a resilient portion having two grooves engageable with said fixed projection.

3. A switch as claimed in claim 1 wherein detent means is provided for maintaining the rotor in anyone of a plurality of angular positions relative to the base.

4. A switch as claimed in claim 3 wherein said plurality of angular positions comprises a first central position wherein no electrical circuits are completed through said first set of electrical contacts a second position achieved by moving the rotor in one angular direction from said first position and in which a first electrical circuit is completed through said first set of electrical contacts, and a third position achieved by moving the rotor in the other angular direction from said first position and in which a second electrical circuit is completed through said first set of electrical contacts.

5. A switch as claimed in claim 4 wherein said first and second electrical circuits are completed during the respective movements of the rotor from the first position, prior to the rotor reaching its second or third positions respectively, and the switch includes means operable during movement of the rotor from its first position to its second position or its third position, to impart resistance to further movement of the rotor to its first position or its second position, said means being operable at points in the movement of the rotor such that said first circuit or said second circuit is completed, but where upon release of the rotor the rotor will be returned by said detent means to the first position.

6. A switch as claimed in claim 5 wherein said means for imparting resistance to movement of the rotor includes a member movable with the rotor and a channel on the base, said member being resiliently urged into engagement with the channel and resistance to movement of the rotor being imparted by engagement of said member with either end wall of the channel.

7. A switch as claimed in claim 4 wherein the rotor carries a pair of resilient arms adapted to be engageable in use in the second and third positions of the rotor respectively by a cancelling striker which rotates with the steering column of the vehicle utilizing the switch, said arms serving to transmit cancelling movement of the striker to the rotor to return the rotor from either of its second and third positions to its first position.

8. A switch as claimed in claim 7 further including a striker mounted for rotation on the base.

9. A switch as claimed in claim 7 wherein said arms are engaged as a snap fit with the rotor.
